United States Patent Office

Des. 216,637

Patented Feb. 24, 1970

216,637

HOLDER FOR FOODS

Harry J. Hermalin, 1961 Vista Del Mar,
Los Angeles, Calif. 90028

Filed Nov. 4, 1968, Ser. No. 14,293

Term of patent 14 years

Int. Cl. D9—04

U.S. Cl. D9—242

The bottom, not shown, is plain and unornamented.

I claim:

The ornamental design for a holder for foods, substantially as shown and described.
